UNITED STATES PATENT OFFICE.

HARVEY L. FISHER, OF WOODSTOCK, ILLINOIS, ASSIGNOR, BY DIRECT AND MESNE ASSIGNMENTS, TO FISHER MANUFACTURING COMPANY, OF CHICAGO, ILLINOIS.

TYPE-WRITING MACHINE.

1,107,664.

Specification of Letters Patent. Patented Aug. 18, 1914.

Application filed April 6, 1897. Serial No. 631,037.

To all whom it may concern:

Be it known that I, HARVEY L. FISHER, a citizen of the United States, residing at Woodstock, in the county of McHenry and 5 State of Illinois, have invented a new and useful Type-Writing Machine, of which the following is a specification.

My invention relates to that class of machines that make impressions upon the top 10 of the cylindrical platen and the writing visible as it proceeds.

My object is to attain simplicity and economy in constructing and efficiency and durability in operation.

15 Heretofore U-shaped type bars have been mounted in two distinct groups and each bar adapted to carry three letters or type differing in form in such a manner that by shifting the platen the different forms of 20 type could be used at pleasure and I purpose to construct and arrange simple curved type bars in four groups to advantageously accomplish the results contemplated by the use of U-shaped bars in two groups, a de- 25 sideratum of importance in view of the fact that it is impracticable to assemble a sufficient number of bars when each of them carries only two letters or type, because some in each group would necessarily have 30 to be of too great length to prevent bending. By increasing the number of groups and arranging them relative to each other and the platen each type bar need carry only two letters or type and the platen needs only 35 a single-shift mechanism in place of a double shift as is required in the use of U-shaped bars in two groups and therefore by my arrangement of the four groups I can alternately print lower and upper case letters in 40 one line as required in writing letters &c.

My invention consists in the construction, arrangement and combination of parts as hereinafter set forth, pointed out in my claims and illustrated in the accompanying 45 drawings, in which—

Figure 1 is a top view showing the relative positions of the four groups of triangular-shaped frames adapted to support series of curved type bars that differ in lengths and 50 move in different planes to successively strike at one and the same center and print letters and characters in true alignment. Fig. 2 is a side elevation showing the manner of mounting the triangular-

shaped frames upon the base in front of the 55 platen to incline upward relative to the platen; also showing the manner of connecting the type bars journaled to said frames with the key levers inclosed in the base and also shows the positions of the feed 60 rolls relative to the platen and the mechanism for operating them. Fig. 3 is an enlarged view of one of the triangular-shaped frames showing the manner of mounting the journals of the type bars therein. Fig. 4 is 65 a transverse section and Fig. 5 an edge view thereof. Fig. 6 is a detail view showing the manner of connecting the type bars journaled to the triangular-shaped frame with the key levers.

70 The letter A designates the base of the machine; A² the frame that supports the sliding carriage A³ and A⁴ the cylindrical platen carried by the carriage.

Nos. 1, 2, 3, 4, are frames of triangular 75 shape mounted upon posts or supports B that are fixed upon the top of the base, as shown in Fig. 2, or in any suitable way, in such a manner that they will incline upward in front of the platen A⁴ at an angle and in 80 such positions relative to each other and the platen as shown in Fig. 1.

A series of reentering angles are formed in the edge of the long side of each of the triangular frames corresponding in number 85 with the series of the type bars journaled thereto. Bores extend through each reentering angle of the frame to the opposite edge. They are enlarged at their extremities to admit cone-shaped washers c on the ends of 90 journals c' of the spindles c''. The curved type bars d that differ in length are fixed to the shouldered ends of the spindles in any suitable way so they can be independently vibrated as required to successively strike 95 the types carried on their free ends upon one and the same center and on top of the cylindrical platen to print letters and words in alignment upon paper carried on the platen.

100 Each type bar d in each series mounted in the frames Nos. 1, 2, 3, 4, is connected with a key lever F, as shown in Fig. 2 in such a manner that when a key lever is depressed at its free end the type bar connected therewith will be actuated as required to print an 105 impression with one of the letters of the type on its free end upon the paper carried on the platen.

It will be seen by reference to Fig. 2 of the drawings that an operator seated in position to operate the machine will be able to look over the top of the type bars and view the writing upon the platen, the type bars when at rest in their normal position being out of the line of sight from the operator to the writing line.

Suitable platen-shift mechanism, which 10 need not be illustrated or described in detail, is employed for the printing of upper or lower case characters as desired; and the lateral movements of the platen, under the operation of the keys, is controlled by the 15 usual or other suitable escapement mechanism, of which the rack T and dog V are shown in Fig. 1.

From the foregoing description of the construction and function of each element and 20 sub-combination of my invention the operation and utility of the machine may be readily understood by persons familiar with the art to which it pertains.

I claim as my invention:

25 1. In a writing machine, the combination, with the platen, of four groups of curved type bars graduated in length and each fixed to an axle, the axles of each group being journaled to a triangular-shaped frame, said 30 type bars being arranged at such angles relative to each other as to allow them to pass each other on their descent to the platen and bring their type to a common printing point on the platen, and their normal positions being out of the line of sight from the operator to the writing line.

2. In a type writing machine a triangular-shaped frame having a series of cone-shaped bearings for supporting type bars in front 40 of a cylindrical platen, arranged and combined with a platen in the manner set forth.

3. A triangular-shaped frame having re-entering angles in one of its edges, a series 45 of straight parallel bearings extending through from said reentering angles, said bearings being enlarged at their extremities, cone-shaped washers fitted in said bearings, and axles fitted in said bearings and washers

as shown and described for the purposes stated.

4. In a type writing machine four groups of upwardly inclined triangular-shaped frames each having parallel bearings, axles extended through said bearings, type bars fixed to the ends of said axles, means for connecting the type bars with the key levers, and a cylindrical platen in a plane above and in rear of said groups of triangular-shaped frames, all arranged and combined as shown and described for the purposes stated.

5. In a type writing machine, the combination with a platen of a right angled triangle shaped bearing frame located in front of the platen, and having a series of parallel cone-shaped bearings for type bars, and type 65 bars journaled in said bearings, substantially as described.

6. In a typewriting machine, the combination, with a platen, of a triangular-shaped bearing frame located in front of the platen 70 and having a series of parallel bearings for type-bars, and a series of typebars mounted on axles arranged in said bearings, said axles being of successively increased length from the one nearest the printing point on 75 the platen to the one most remote, and being located in a plane substantially tangential to the platen and inclined forwardly and downwardly therefrom.

7. In a typewriting machine, the combination with a platen of a series of bearing frames, each consisting of a substantially right angled triangle shaped plate of metal provided with a series of parallel bearings for type bars, said bearing frames being located in front of the platen and each having an apex directed toward the printing point and being inclined upwardly from its outer side thereto, means for supporting said bearing plates, and type bars journaled in said 90 bearings, substantially as described.

HARVEY L. FISHER.
